UNITED STATES PATENT OFFICE

CLARE H. DRAPER, OF HOPEDALE, MASSACHUSETTS, ASSIGNOR TO DRAPER CORPORATION, OF HOPEDALE, MASSACHUSETTS, A CORPORATION OF MAINE

POSITIVE LET-BACK MECHANISM FOR LOOMS.

Application filed February 18, 1930. Serial No. 429,408.

This invention relates to the take-up mechanism of a loom and has for its primary object to provide means acting to secure an accurate, uniform, and positive amount of let-back or rotary shift of the take-up roll when required in the operation of the loom to prevent a thin place in the cloth being woven.

The invention is concerned with a loom provided with mechanism for effecting a change in the operation of the loom, such, for example, as an automatic replenishment of the running filling, upon the occurrence of a filling fault. For this purpose the loom is usually provided with a filling fork which feels for the filling at each pick and which, if the filling is absent by reason of breakage or exhaustion of the running supply, acts through suitable mechanism automatically to replenish the supply of running filling. When this occurs, one or more picks have not been laid, although the action of the take-up has been proceeding, and it is necessary to reverse the rotation of the take-up mechanism, or otherwise shift the rotary position of the take-up relatively to its drive, or else a thin place would occur in the cloth.

In the usual form of let-back mechanism, the take-up roll is momentarily disconnected from its driving mechanism and the pull or tension on the cloth acts to effect reverse rotation of the take-up roll. Hence the amount of let-back is more or less indefinite and uncertain resulting in imperfections in the cloth, especially in the finer grades and with certain types of yarn.

The present invention provides a construction in which the connections from the driving element to the take-up roll are permanently maintained both during the taking up and the letting back movements and in which these connections are positively, uniformly, and accurately operated to drive the take-up roll in the one direction to effect take-up, and, when let-back is required or a thin place is to be prevented, to effect a relative rotary shift of the take-up roll with respect to the driving element to decrease or reverse the rotation of the take-up roll thus to effect let-back or to prevent the formation of a thin place in the cloth.

In the preferred form of the invention, these driving connections include a planetary or differential system of gears in which the revolute gears are carried by a housing. When the take-up roll is being driven to effect take-up, the housing is held against rotation and when let-back is required, the housing is positively rotated. Thus the driving connections are unbroken, are never disconnected in the operation of the loom, and remain permanent throughout the operation of the loom.

The invention has as its further object to provide for the required positive, relative, rotary shift of the take-up roll to effect let-back or to prevent a thin place from the movement of the usual filling fork slide which, when a filling fault occurs, is given a definite, positive, sliding movement and which is in turn imparted to the take-up roll.

These and other features of the invention will appear more fully from the accompanying description and drawings and will be particularly pointed out in the claims.

The drawings illustrate so much of a well-known type of loom as is necessary to a disclosure of the invention, together with a preferred form of the invention embodied therein.

In the drawings:

Fig. 1 is a left-hand side elevation partially broken away of the front end of the loom.

Fig. 2 is a front elevation of the construction shown in Fig. 1.

Fig. 3 is a detail chiefly in vertical cross section taken on the line 3—3 of Fig. 1.

Fig. 4 is a view in side elevation and partially in vertical cross section on the line 4—4 of Fig. 2.

Fig. 5 is an enlarged detail partially in vertical cross section of the ratchet and operating mechanism therefor shown in Fig. 2.

The loom comprises the usual side frames, of which a portion of the left-hand frame 1 is shown with the breast beam 2 extending therefrom to the opposite side frame. A usual form of take-up roll 3 is journaled in the side frames under the breast beam and usually presents a roughened surface to grip the cloth which is wound on the cloth roll 4 by frictional engagement with the

take-up roll. A shaft 5 is journalled in a bearing bracket 6 supported on the bottom of the frame and this shaft has journalled thereon a gear 7. A train of gearing which 5 may be of any suitable arrangement and indicated generally at 8 extends from the gear 7 to the shaft 9 of the take-up roll so that any rotation imparted to the gear 7 will in turn be positively and definitely imparted to the 10 take-up roll. But it will be understood that the particular driving connections between the element 7 and the shaft 9 of the take-up roll may be of any suitable construction so long as they act to impart positively, directly, 15 and accurately the rotation of the take-up roll in either direction according to the direction of rotation of the element 7.

The shaft 5 has keyed thereto at 10 a worm wheel 11 and this worm wheel meshes with 20 and is driven by a worm 12 keyed to a shaft 13 journalled in the bearing bracket 6 and extending rearwardly in the loom frame and positively driven from one of the usual loom shafts. The shaft 5 has keyed thereon at 25 14 a driving element in the form of a bevelled gear 15.

The elements thus described, by means 30 of which the driving element or bevelled gear 15 is given a positive rotation, may be of any suitable form and construction and specifically considered form no part of the present invention.

A driven element in the form of a bevelled gear 16 is journalled in axial alignment with 35 the driving element or bevelled gear 15 and is preferably, for that purpose, journalled on the shaft 5. This driven element 16 is the one which imparts a direct driving connection to the take-up roll and for that purpose 40 is preferably formed rigid or integral with the gear 7 and thus acts through the train of gearing 8 to drive the take-up roll.

A differential system of gearing is illustrated, including the bevelled gears 15 and 45 16, and comprises a cylindrical housing 17 with one or more intermediate bevelled gears 18, herein shown as three in number, having their shafts 19 journalled radially therein and so arranged that the bevelled gears 18 50 mesh with both of the bevelled gears 15 and 16.

The outer cylindrical surface of the housing 17 is formed to present a worm wheel 20 and this worm wheel 20 meshes with a 55 worm 21 secured to an auxiliary or transverse shaft 22 journalled in portions 23 of the bearing bracket 6.

It will thus be seen that under normal conditions with the shaft 22 immovable, the 60 worm 21 will lock the housing 17 against rotation so that as the shaft 13 is rotated, a direct positive drive will be imparted from the driving element 15 through the intermediate gears 18 to the driven element 16 and therefrom to the take-up roll to effect take-

up. The take-up roll will then be driven positively from the driven element at a fixed ratio of speed, depending upon the proportions of the driving connections therebetween. If now rotation be imparted to the auxiliary shaft 22, the housing 17, which is the intermediate element of the differential gearing, will be positively rotated and such rotation will effect a relative rotary shift or change in angular relation between the take-up roll and the driving element. Consequently, by rotating the auxiliary shaft 22 in the proper direction, the rotation of the take-up roll will actually decrease or be reversed according to the relative speed of rotation of 80 the shaft 22. This rotation of the auxiliary shaft 22 therefore shifts the rotary position of the take-up roll with respect to the driving element without in any way disturbing the permanency of the connections extending 85 from the driving element to the take-up roll. Thus the movement of the take-up roll to effect let-back or to prevent a thin place is secured positively, accurately, and to an exact predetermined degree. If, when the auxiliary shaft 22 is rotated, the loom is stopped and the driving element 15 is thus held against rotation by the worm 12, then the movement imparted by the auxiliary shaft 22 to shift the relative rotary position of the 90 take-up roll with respect to the driving element is entirely devoted to a reversal of the actual rotary movement of the take-up roll. Thus in any event, when let-back is required or a thin place is to be prevented, the take-up 95 rotation of the take-up roll is positively counteracted to compensate for the loss of picks due to a filling fault and to prevent the formation of a thin place in the cloth.

In the preferred form of the invention, rotation is imparted to the auxiliary shaft 22 thus to effect let-back or prevent a thin place, upon the occurrence of a filling fault, by connections positively and accurately operated from the filling fork slide which in turn is 100 positively and accurately operated by the usual mechanism employed for that purpose 110 in the loom.

A filling fork slide 24 of a usual type is shown mounted to slide forward and rearward on the top of the breast beam and has pivotally mounted at 25 in its rearward end a filling fork having the depending tines 26 and the looped forward end 27. A weft hammer 28 of the usual type is fulcrumed at 29 in the loom frame and at its rearward end carries a follower 30 riding on a cam 31 on the cam shaft 32 of the loom. If the filling is properly laid in the shed, it engages the tines 26 on the beat-up and the filling fork is rocked, raising the looped end 27. If the filling is broken or exhausted or otherwise in fault, the fork 26 is not rocked and the looped end 27 catches on the end of the weft hammer 28 so that as the cam 31 revolves, the 115 120 125 filling fork slide is given a positive, accurate, and definite forward movement and, at the same time, through connections familiar to those skilled in the art, the desired change is effected in the operation of the loom such as the automatic replenishment of the running filling or such as the stopping of the loom. It is this movement of the filling fork slide, or a portion of this movement, that is here preferably utilized for rotating the auxiliary shaft 22 to effect let-back or prevent a thin place.

A ratchet wheel 33 is keyed at 34 to the shaft 22. A pawl carrier in the form of a sector-shaped casing 35 is journaled on the shaft 22 surrounding the ratchet wheel and has pivoted thereto at 36 a pawl 37 cooperating with the ratchet wheel 33 and normally held in engagement therewith by a helical spring 38 seated in a pocket in an extension 39 of the pawl and abutting the outer surface of the carrier casing 35. The pawl carrier casing 35 is oscillated through suitable adjustable connections extending upward therefrom by the filling fork slide.

The connections for thus operating the pawl carrier from the filling fork slide are illustrated in a simple and preferred form. A bell crank lever is fulcrumed at 40 in a bracket 41 bolted to the breast beam. The upstanding arm of this bell crank lever is in the form of a plate 42 which extends at the front of the end of the filling fork slide. This arm is yieldingly drawn toward the filling fork slide by a spring 43 connected at the forward end to a stud 44 extending from the arm 42 and at the rearward end to a stud 45 on the breast beam. A set screw 46 in the arm 42 adjustably determines the rearward movement of the bell crank lever under the influence of the spring 43 and thus the point in the forward movement of the filling fork slide when the filling fork slide will engage with the bell crank lever and begin to impart a positive forward movement thereto. The forwardly extending arm 47 of the bell crank lever has adjustably connected thereto a link 48, this adjustment being effected by placing a stud 49 in one or the other of the holes 50 in the arm 47. The lower end of the link 48 is pivoted at 51 in a bifurcated arm 52 journaled on a shaft 53 which may be the usual starter rod found on looms of this type. A two-part link 54, 55 adjustably connected together by the bolt 56 is pivotally connected at its upper end at 57 to the arm 52 and at its lower end at 58 to the pawl carrier casing 35.

Such a means as that described thus causes let-back to take place or a thin place to be prevented by a positive, accurate, and predetermined movement without disturbing the permanency of the connections which extend from the driving element to the take-up roll. Furthermore, such a construction provides

means by which the extent or degree of the decrease in the rotation or the reverse rotation of the take-up roll may be varied as required.

When a filling fault occurs and a change in the operation of the loom, such as a replenishment of the filling, takes place with the loom continuing to run, the cam 31 acts through the weft hammer to give a definite and positive degree of movement to the weft fork slide. By the adjustment of the set screw 46, the bell crank lever 42, 47 is adjusted in position so that the entire movement, or any desired portion of the entire movement, of the slide will be positively imparted thereto. By the adjustment of the upper pivotal point 49 of the link 48 into one of the holes 50, the amount of movement imparted to the bell crank lever is imparted in a predetermined amount through the connections described to the pawl carrier 35. As a result, the ratchet 33 is moved and therewith the worm 21 to rotate the housing 17 and consequently, as described, the rotary angular position of the take-up roll is shifted relatively to the driving element without disturbing the permanent connections therebetween. This may be simply a decrease in the actual rotation of the take-up roll or an actual reversal of rotation. But in any event a thin place in the cloth is prevented.

If, when the filling fault occurs, the loom is stopped, then the driving element 15 is held against rotation by the worm 12 and the rotation of the housing 17 acts positively to effect a reverse rotation of the take-up roll to effect the required let-back.

The shaft 5 is provided at the ends with collars 59 and 60 secured thereto to hold the parts in proper position. A hand wheel 61 is mounted on the end of the auxiliary shaft 22, thus enabling the auxiliary shaft to be turned manually when it is desired to adjust or set the take-up roll in proper position. A friction brake is also provided on the auxiliary shaft 22 to prevent any lost motion, overthrow or slippage of the connections. This is shown as comprising a drum 62 secured to the shaft 22 and a bifurcated or split collar 65 encircling the drum, a stud 66 extending from one of the bearing portions 23 of the bracket 6 and entering a slot 67 in the collar to prevent rotary movement thereof, a pin 68 passing through one member 69 of the collar and secured in the other member 70 and a spring 71 surrounding the pin and abutting at one end against the member 69 and at the other end against the head 72 of the pin and acting to clamp the collar yieldingly against the drum on the shaft 22.

Having thus described the invention, what is claimed as new, and desired to be secured by Letters Patent, is:

1. A loom comprising a take-up roll, a driving element, a permanent positive driv-

ing connection from the driving element to the take-up roll acting to rotate the take-up roll at a fixed ratio of speed with respect to the driving element to effect take-up, and

5 means acting upon the occurrence of a filling fault to shift the angular relation of the take-up roll with respect to the driving element to prevent a thin place in the cloth.

2. A loom comprising a take-up roll, a 10 driving element, a permanent positive driving connection from the driving element to the take-up roll acting to rotate the take-up roll at a fixed ratio of speed with respect to the driving element to effect take-up, means

15 acting upon the occurrence of a filling fault positively to rotate the take-up roll with respect to the driving element to decrease or reverse its taking up movement to a predetermined extent thus to effect let-back or 20 prevent a thin place in the cloth.

3. A loom comprising a take-up roll, means for driving the take-up roll to effect take-up, means acting upon the occurrence of a filling fault to effect a change in the operation of 25 the loom, and means acting thereupon positively and without disconnection of the take-up roll from its driving means to counteract to a predetermined degree the take-up rotation of the take-up roll to compensate for 30 the loss of picks caused by said fault.

4. A loom comprising a take-up roll, a driving element, a differential system of gearing between the driving element and the take-up roll for driving the latter from the 35 former to effect take-up, means acting upon the occurrence of a filling fault to effect a change in the operation of the loom, and means acting thereupon positively to rotate bodily and to a predetermined extent the intermediate element of the differential gearing 40 to shift the rotary position of the take-up roll with respect to the driving element in a direction to effect let-back or prevent a thin place in the cloth.

5. A loom comprising a shaft, means for positively driving the shaft, a driving gear secured to the shaft, a driven gear journalled in axial alignment with the shaft, a take-up roll, a gearing connection between the take-up roll and the driven gear, a housing, an intermediate gear journalled in the housing and meshing with the driving and driven gears, an auxiliary shaft, a gearing connection between the auxiliary shaft and housing, the said auxiliary shaft normally acting to hold the housing against rotation and thus enable the take-up roll to be driven positively to effect take-up, and means actuated when let-back is required to rotate the auxiliary shaft a predetermined degree thereby to effect positively the desired amount of let-back.

6. A loom comprising a shaft, means for positively driving the shaft, a driving gear secured to the shaft, a driven gear journalled in axial alignment with the shaft, a take-up

roll, a gearing connection between the take-up roll and the driven gear, a housing, an intermediate gear journalled in the housing and meshing with the driving and driven gears, an auxiliary shaft extending transversely of the housing, a worm on the auxiliary shaft, a worm wheel on the housing cooperating with the said worm, the said auxiliary shaft normally acting to hold the housing against rotation and thus enable the take-up roll to be driven positively to effect take-up, and means actuated when let-back is required to rotate the auxiliary shaft a predetermined degree thereby to effect positively the desired amount of let-back.

7. A loom comprising the construction defined in claim 5, together with a friction brake secured to the loom frame and engaging the auxiliary shaft to prevent undesired movement thereof.

8. A loom comprising the construction defined in claim 5, together with a hand wheel secured to the auxiliary shaft thus to enable the take-up roll to be turned manually in either direction.

9. A loom comprising a shaft, means for positively driving the shaft, a driving gear secured to the shaft, a driven gear journalled in axial alignment with the shaft, a take-up roll, a gearing connection between the take-up roll and the driven gear, a housing, an intermediate gear journalled in the housing and meshing with the driving and driven gears, an auxiliary shaft, a gearing connection between the auxiliary shaft and housing, the said auxiliary shaft normally acting to hold the housing against rotation and thus enable the take-up roll to be driven positively to effect take-up, a filling fork, a filling fork slide, means for imparting a definite, positive, sliding movement to the slide upon indication of filling absence by the fork, and means actuated by the said movement of the slide to rotate the auxiliary shaft a predetermined degree thereby to effect positively the desired amount of let-back.

10. A loom comprising a shaft, means for positively driving the shaft, a driving gear secured to the shaft, a driven gear journalled in axial alignment with the shaft, a take-up roll, a gearing connection between the take-up roll and the driven gear, a housing, an intermediate gear journalled in the housing and meshing with the driving and driven gears, an auxiliary shaft, a gearing connection between the auxiliary shaft and housing, the said auxiliary shaft normally acting to hold the housing against rotation and thus enable the take-up roll to be driven positively to effect take-up, a filling fork, a filling fork slide, means for imparting a definite, positive, sliding movement to the slide upon indication of filling absence by the fork, and a pawl and ratchet connection between the slide and the auxiliary shaft acting upon the said

movement of the slide to rotate the auxiliary shaft thereby to effect positively the desired amount of let-back.

11. A loom comprising a take-up roll, means for driving the take-up roll to effect take-up, means acting to effect a change in the operation of the loom upon the occurrence of a filling fault, and means acting thereupon permanently connected with the take-up roll to give positively a definite predetermined amount of rotary shift of the take-up roll relative to its driving means to prevent a thin place in the cloth.

12. A loom comprising a take-up roll, means for driving the take-up roll to effect take-up, means acting to stop the loom upon the occurrence of a filling fault, and means acting upon the stoppage of the loom, and without disconnecting from the take-up roll the means for driving it, to give a definite predetermined amount of positive reverse rotation to the take-up roll to effect let-back.

13. A take-up and let-back mechanism for looms comprising a driving element, a take-up roll, a train of permanent connections between said driving element and roll, and means for holding one of said connections against movement and to permit the rotation of the take-up roll to effect take-up when take-up is required and for moving the said connection to decrease or reverse the rotation of the take-up roll thereby to effect let-back or prevent a thin place as required.

14. A take-up and let-back mechanism for looms comprising a driving element, a take-up roll, a train of permanent connections between said driving element and roll, one of said connections being rotatably mounted and acting when held against rotation to permit the driving element to rotate the take-up roll to effect take-up, and means acting upon the occurrence of a filling fault to rotate the said connection to decrease or reverse the rotation of the take-up roll thereby to effect let-back or prevent a thin place.

15. A take-up and let-back mechanism for looms comprising a driving element, a take-up roll, a train of permanent connections between said driving element and roll acting to rotate the roll to effect take-up and means for positively moving one of said connections, when the driving element is at rest, to reverse the rotation of the take-up roll thereby to effect let-back.

16. A take-up and let-back mechanism for looms comprising a driving element, a take-up roll, a train of permanent connections between said driving element and roll acting to rotate the roll to effect take-up and means, actuated upon the occurrence of a filling fault, to move one of said connections to decrease or reverse the rotation of the take-up roll to effect let-back or prevent a thin place.

17. A take-up and let-back mechanism for looms comprising a take-up roll, means for

positively rotating the take-up roll either in a direction to effect take-up or in the reverse direction to effect let-back, the said means including an element held stationary during rotation of the take-up roll to effect 70 take-up and moved to effect that rotation of the take-up roll required to effect let-back.

18. A loom comprising a take-up roll, means for driving the take-up roll to effect take-up, said means permanently connected 75 with the take-up roll, a filling fork, a filling fork slide, means for imparting a definite, positive, sliding movement to the slide upon indication of filling absence by the fork, and connections between the slide and the take-up roll driving means acting upon the said movement of the slide to give positively a definite predetermined amount of rotary shift of the take-up roll relatively to its driving means to prevent a thin place in the 85 cloth.

In testimony whereof, I have signed my name to this specification.
